UNITED STATES PATENT OFFICE

WEBSTER L. DIEHL, OF KING CITY, MISSOURI.

DISPLAY ATTACHMENT FOR CONTAINERS.

Application filed July 15, 1924. Serial No. 726,117.

To all whom it may concern:

Be it known that I, WEBSTER L. DIEHL, a citizen of the United States, residing at King City, in the county of Gentry and 5 State of Missouri, have invented certain new and useful Improvements in Display Attachments for Containers, of which the following is a specification.

This invention has more especial reference 10 to a display attachment to be hingedly connected to a box or container and embodying two connected members one of which constitutes a transparent cover or lid for the box or container, through which the contents are displayed while protected against 15 atmospheric influences, and the other of which members provides a framing adequate to carry and display, an effective advertising device relating, for example, to the 20 articles contained in and to be vended from the box or container,—cigars, for instance.

The ultimate purpose accomplished by the present invention is the provision of an attachment of the type stated which will be 25 characterized severally by its strength and durability; by the facility it affords for a hinged connection with the box or container including the freedom with which it may be applied or removed without any loss of 30 time in its application or removal; and also by the facility it affords for an effective and attractive display of advertising matter relating to the goods displayed by and vended from the box.

35 In the accompanying drawings illustrating certain preferred embodiments of the invention, and in which drawings similar letters of reference denote corresponding parts in the several views:—

40 Fig. 1 is a perspective view of a container having my improved attachment applied to the hinged lid thereof, showing in full lines the position of the parts when the box is closed by the supplemental cover and in 45 dotted outlines the position of the parts when the supplemental cover is partially raised but sufficiently to give access to the interior of the container.

Fig. 2 is a vertical section through the box 50 lid and the attachment and the upper part of the container.

Figs. 3 and 4 are perspective views of the attachment without the container, showing 55 slightly different embodiments of the invention.

I have illustrated and will hereinafter de-

scribe my invention as applied to a box or container having a hinged lid, in which event the lid serves as the means by which the attachment is hingedly connected to the 60 body of the container. It, however, should be understood that the attachment may be applied to containers whose lids are not hinged and are entirely removed when the attachment is in use on the container, merely 65 by providing the attachment with a suitable means to connect it hingedly to the body of the container or by providing the container with a suitable means to attach the attachment hingedly thereto, without departing 70 from the spirit of the invention as defined by appended claims.

A designates the body of a container which may be of any ordinary or approved 75 size and construction and A' designates the hinged lid thereof.

The attachment which constitutes the present invention comprises two frames, marked C and D, respectively, rigidly secured together at a suitable angle with each 80 other by a transverse member E.

The frame C carries a transparent member F, preferably of plate glass, which serves as the cover for the box when the attachment is applied, and comprises side members c and a front member c' arranged to form a frame which is closed at its sides and front and open at its rear. Each of these members is of channel form in cross section, each comprising upper flanges 10 and lower 90 flanges 11 spaced from each other to receive an edge of the supplemental cover F between them. This cover member F is inserted into the frame C through the open rear side of the latter and is slid to its 95 operative position in the frame, with its forward edge in the channel of the front member and its side edges in the channels of the side members of the frame. It is not necessary that it be secured in place 100 by putty or any means other than the frame itself.

The frame D comprises two longitudinal members d and a suitable transverse member. Each longitudinal member is of channel form in cross section, comprising forward flanges 12 and rear flanges 13. The transverse member may be of similar channeled form, as shown in Figs. 1, 2 and 3, in which it is marked d', or it may be a flat bar or strip as shown at d'' in Fig. 4. When of channel form, it is mounted at the 110

top of the frame and connects the upper extremities of the side members d with each other, and when of the form shown at d^{10} it may be mounted at any suitable place 5 along the length of the frame, but preferably near the top thereof, and is secured at its opposite ends to the surfaces of the flanges 13 of the side members d . The construction first described provides a frame 10 which is closed along its sides and top and open along its bottom: while the other construction (Fig. 4) provides a frame which is closed along its sides and open at its top and bottom. In both forms, the transverse members (d' , d^{10}) acts as a brace which 15 holds the side members in proper relative position and adds rigidity to the frame.

The member E hereinbefore referred to 20 is of suitable angular form in cross section, comprising two webs or limbs 14 and 15. The web or limb 14 is secured at its opposite ends to the upper flanges 10 of the side members c of the frame C; while the web or limb 15 is secured at its opposite ends to 25 the front faces 12 of the side members d of the frame D. This member acts as a brace for the rear end of the frame C and lower end of the frame D and secures the two frames together into a unitary structure. 30 It will be noted that it is mounted above the frame C and at the front of the frame D and hence does not interfere with the free insertion of the supplemental cover F into the frame C or its removal from said 35 frame, or interfere with the application of the member D to or its removal from the lid A', or the free insertion or removal of the other elements which are to be mounted in said member D.

40 These other elements preferably include a card G containing appropriate matter of advertising or other nature and a transparent plate H mounted in front of and protecting the card G as well as increasing the 45 attractiveness of the display of said matter and giving strength and rigidity to the lid A'.

It will be understood that the parts are 50 assembled by inserting the plate F into the frame C from the rear end of the latter and that the plate H is inserted into the frame D from the bottom of the latter, there being no obstruction to the free entry of the plates into the respective frames at the 55 place where these two ends of the frame meet each other. When the parts of the attachment have been assembled the plate H rests with its bottom edge on the rear end of the plate F.

60 The attachment may then be quickly applied to the lid A' by inserting the lower end of its frame upon the lid at the upper corners of the latter and then pressing it to its place lengthwise of the lid, with its lower 65 end at the bottom of the lid. When thus

applied, the frame F will be so located that when the lid is in the raised position shown the supplemental cover will rest upon the body of the box and close the same against atmosphere influences while displaying the 70 contents thereof; and the frame D will stand in a substantially upright position with the lid A', with the advertising matter on the card G attractively displayed through and protected by the plate H. It will be 75 apparent that the attachment may be swung to open and close the box and that its swinging movement is with the lid and about the axis of the hinge or hinges which 80 connect the lid to the body of the box. 85

It will be noticed that the frame D has long bearings upon the lid A' and together with the transverse members E and d' , or d^{10} , give stiffness to the lid: and further that the plate H which is co-extensive with the 90 lid protects the latter against all liability of breakage under any strain imposed thereon in opening and closing the supplemental cover. In fact, it will be noticed that without this plate H, the weight of the parts of the attachment in opening and closing the box is so distributed by reason of the length of the frame D and its engagement with the lid that there is slight liability of breakage 95 of the lid, even when the latter is made of flimsy material as is usual in the case of cigar boxes, and moreover, it will be noticed that the length of the frame D affords opportunity for a very attractive and effective card of advertising or other nature, 100 which, of course, may be changed as is necessary or desirable. It will, of course, be apparent that the display card may be omitted and the transparent member H used to expose the label, if there be one, on the lid and it will also be apparent that the display card may be used without said transparent member and further that both the transparent member referred to and the display card may be omitted; but I greatly prefer 105 to use the transparent member, whether the display card is used or not, in part because of the additional strength which said member imparts to the lid. Finally, I would have it understood as already suggested that if the container to which the attachment is applied be one unprovided with a hinged lid, the attachment may be applied to the 110 container by any suitable means of a pivotal nature, preferably connected to its member E and being of a kind which permits ready application and removal of the attachment. 115

I will have it understood that other changes in details may be made without departing from the spirit of the invention as 120 defined by appended claims.

Having thus described the invention, what I believe to be new and desire to secure by Letters Patent, is:—

1. An attachment for a container having 125

a hinged lid, comprising two frames arranged at an angle with each other and a member rigidly connecting said frames to each other to form a unitary structure, one of said frames being adapted to be mounted on the lid of the container and the other containing a member through which the goods in the container are displayed.

2. An attachment for a container, comprising two frames arranged at an angle with each other and a member rigidly connecting said frames to each other to form a unitary structure, each of said frames having side members formed with longitudinal channels, and a transparent cover member having its edges in the channels of the side members of one of the frames.

3. An attachment for a container comprising two frames arranged at an angle with each other and a member rigidly connecting said frames to each other to form a unitary structure, each of said frames having side members formed with longitudinal channels, and a transparent cover member having its edges in the channels of the side members of the one of the frames, the latter frame also having a transverse member which closes its front end and is channeled to receive the front edge of said member, and being open at its rear end to permit the insertion thereof.

4. An attachment for a container having a hinged lid, comprising two separate frames arranged at an angle with each other and a transverse member rigidly connecting said frames to each other at the junction thereof, one of said frames being adapted to be mounted on the lid of the container and comprising side members and a transverse member which connects the side members with each other at a place substantially above the bottom of the frame, and a transparent member carried by the other frame and through which the goods in the container are displayed.

5. An attachment for a container, comprising two separate frames arranged at an angle with each other and a transverse member rigidly connecting said frames to each other at the junction thereof, one of said frames comprising side members having longitudinal channels and a transverse member which braces the upper part of the frame, and the other frame also having longitudinally channeled side members, and a transparent cover member carried by the side members of the latter frame with its edges in the channels thereof.

6. An attachment for a container, comprising two separate frames arranged in juxtaposition with each other in an angular relation and each having longitudinal channels open at their adjacent portions of the frames, a member arranged across the front of the attachment at the junction of said

frames and rigidly connecting the frames to each other without closing the open ends thereof, one of said frames having a transparent member through which the goods in the container are displayed.

70

7. An attachment for a container having a hinged lid, comprising a frame having a transparent member through which the goods in the container are displayed, a second frame having longitudinally channeled side members to receive the lateral edges of the lid, and a member rigidly connecting the two frames to each other.

75

8. An attachment for a container, comprising a frame having a transparent member through which the goods in the container are displayed, a second frame having longitudinally channeled side members, a member extending across the attachment at the junction of the two frames and rigidly connecting the same together and a second transverse member extending across the second frame above the bottom thereof.

80

9. An attachment for a container, comprising a frame having a transparent member through which the goods in the container are displayed, a second frame having longitudinally channeled side members, a member extending across the attachment at the junction of the two frames and rigidly connecting the same together, and a transparent member mounted in the second frame with its edges in said channels.

90

10. An attachment for a container, comprising a frame having a transparent member through which the goods in the container are displayed, a second frame having longitudinally channeled side members, a member extending across the attachment at the junction of the two frames and rigidly connecting the same together, and a display card mounted in the second frame with its edges in said channels.

100

11. An attachment for a container, comprising a frame having a transparent member through which the goods in the container are displayed, a second frame, having longitudinally channeled side members, and a member extending across the attachment at the junction of the two frames and rigidly connecting the same together, a display card and a transparent member covering said card, the card and transparent member mounted in the second frame with their edges in the channels thereof.

110

12. An attachment for a container, comprising a frame having a transparent member through which the goods in the container are displayed, a second frame, having longitudinally channeled side members, and a member extending across the attachment at the junction of the two frames and rigidly connecting the same together, a second transverse member extending across the second frame above the bottom thereof, and

115

120

125

130

a transparent member mounted in the second frame with its edges in said channels.

13. An attachment for a container, comprising a frame having a transparent member through which the goods in the container are displayed, a second frame having longitudinally channeled side members, a member extending across the attachment at the junction of the two frames and rigidly connecting the same together, a second transverse member extending across the second frame above the bottom thereof and a display card mounted in the second frame, with its edges in said channels.

14. An attachment for a container, comprising a frame having a transparent member through which the goods in the container are displayed, a second frame having longitudinally channeled side members, a member extending across the attachment at the junction of the two frames and rigidly connecting the same together, a second transverse member extending across the second frame above the bottom thereof and a display card mounted in the second frame, with its edges in said channels.

15. An attachment for a container, comprising a frame having a transparent member through which the goods in the container are displayed, a second frame having longitudinally channeled side members, a member extending across the attachment at the junction of the two frames and rigidly connecting the same together, a second transverse member extending across the second frame from above the bottom thereof, a display card and a transparent member covering said card, the card and transparent member being mounted in the second frame with their edges in said channels.

16. An attachment for a container, comprising two frames arranged at an angle with each other and a member rigidly connecting said frames to each other to form a unitary structure, one of said frames containing a transparent member through which the goods in the container are displayed and the other being adapted to frame display matter.

17. A hingeable display attachment for containers, comprising two separate frames, each open at one end, and a transverse member having limbs secured to said frames respectively and uniting the same into a unitary structure, one of said frames containing a transparent member through which the goods in the container are displayed and the other being adapted to frame display matter.

18. A hingeable display attachment for containers, comprising two separate frames, each open at one end, and a transverse member having limbs secured to said frames respectively and uniting the same into a unitary structure, one of said frames containing a transparent member through which the goods in the container are displayed and the other being adapted to frame display matter.

19. A hingeable display attachment for containers, comprising two separate frames, each open at one end, and a transverse member having limbs secured to said frames respectively and uniting the same into a unitary structure, one of said frames containing a transparent member through which the goods in the container are displayed and the other being adapted to frame display matter.

In testimony whereof I affix my signature.

WEBSTER L. DIEHL.
